SAMUEL S. ROBERTS, OF ELIZABETH, PENNSYLVANIA.

Letters Patent No. 92,476, dated July 13, 1869.

IMPROVED COAL-LOADING APPARATUS.

The Schedule referred to in these Letters Patent and making part of the same.

To all whom it may concern:

Be it known that I, SAMUEL S. ROBERTS, of the borough of Elizabeth, in the county of Allegheny, and State of Pennsylvania, have invented a new and useful Improvement in Apparatus for Loading Coal; and I do hereby declare the following to be a full, clear, and exact description thereof, reference being had to the accompanying drawing, making a part of this specification, in which—

Figure 1 is a perspective view of my improved apparatus;

Figure 2 is a sectional elevation, as formed by a vertical plane passing through the apparatus at right angles to the hoisting-drum; and

Figure 3 is a front elevation of a car in the position for dumping its contents down the chute.

Like letters of reference indicate like parts in each.

My improved apparatus, while applicable to loading coal generally, is especially useful for that purpose where the coal is on or contiguous to a navigable stream, by which, when loaded into barges, it is towed to the place of sale, or consumption. The stage of water in such stream, between high and low water, often varies several feet; and if the lower end of the chute, down which the coal is dumped into the boat or barge, be fixed and not adjustable, the distance the coal will have to fall at low water will be so great that the lumps will be broken and crushed, by which the amount of slack or refuse material is largely increased, and the value of the coal considerably lessened.

The object of my invention is to overcome this, and some other difficulties connected with the discharging of coal from cars into boats or other receptacles, by which labor is saved, and the work facilitated.

In the construction of devices adapted to secure such results, consists the nature of my invention.

To enable others skilled in the art to make and use my invention, I will proceed to explain its construction and manner of operation.

a *b* represent any suitable frame-work built on the bank of the river, at any suitable point, on which a track, *a'*, leading from the coal-mine, terminates.

Near the forward part of the frame *B*, is a trap or opening, at the upper part of which is a frame, *a''*, carrying a pair of rails, *a'*. The forward ends of the rails *a* are turned up, as shown, to a sled-runner shape, so as to stop the loaded car when run thereon. The frame *a''* is adjustable up and down.

The chains *f* extend from it, on either side, over a drum, *f'*, and its weight, and that of a loaded car, are counterpoised, in whole or in part, by a weight attached to the chain *f''*.

The operation of the hoisting-drum *f* is regulated by a brake, *g*, of any suitable construction, and brake-levers *g'* connected therewith.

In order to regulate the adjustment of the rails *a* as they descend through the trap, preparatory to discharging the coal from the car thereon, I attach to the rear end of the frame *a''*, hooks *c*, which, when they reach the proper point of adjustment, engage the pins or rods *e*, previously adjusted for that purpose, in holes in the upright posts *V*. At the forward end of the track *a*, I dispense with such means of adjustment. That end of the track continues to descend until the car is automatically unloaded, as presently to be described, when, being empty, the counterweight brings it up, and it is run off to make way for a loaded car.

On the forward part of the frame *b*, and in front of the track *a*, is an adjustable chute *d*, hung, at its opposite ends, to the roller *e* by chains *e'*.

These rollers are operated separately or together, and held at any desirable point of adjustment, by levers, *i*. To give it further support, and steady it in place, its rear end may rest on a cross-bar, *i'*, passing through holes in the posts of the frame *b*, and adjustable higher or lower therein. Then, to adapt the apparatus for use in loading barges at low water, the chute *d* is lowered till, still retaining the inclination necessary for sliding the coal down, its lower and outer end is sufficiently near the level of the barge. The pins *c*, which support the rear end of the trap-frame *b*, are also adjusted at such point that the forward end of the rails *a* will be at or near the upper end of the chute *d*, and still it will be inclined sufficiently to dump the coal out of the open end of the car, as it rests thereon.

To discharge automatically the contents of each car, I make the car *x x* with an end gate, *m*, hinged at its upper edge, and a fastening-bar, *n*, extending across its lower end, held in place by a catch, *n'*. The end of the fastening-bar *n* projects somewhat beyond the side of the car, so as, when the forward end of the car goes down on the trap-rails *a*, the end of the fastening-bar *n* will engage in a tripper, *o*, by which it will be loosened, the end gate opened, and the load discharged from the car, which is tilted forward on the inclined trap-rails *a*, down the chute *d*, and into the boat or barge. If the stage of water be high, the adjustments should be made accordingly.

It is often desirable to screen the coal before loading it into a boat for market, and hence I sometimes make the chute *d* with screen bottom. The slack, &c., is thus separated from the coal as it is loaded.

Any suitable weighing-apparatus may be combined with the devices described, so as to weigh the coal, if so desired, before sending it to market.

What I claim as my invention, and desire to secure by Letters Patent, is—

1. A dumping-frame or tipple, *a''*, adjustable so as automatically to dump the coal from the car at any

desirable elevation, and provided with hooks, *c*, which, engaging a fixed part of the frame, prevent the tipple and car from swinging forward, and also provided with a hoisting-apparatus, substantially as described.

2. A chute or screen, *d*, adjustable so as to be raised or lowered at either end separately, or at both ends together, in combination with a tipple, *a*', constructed

and operated substantially as and for the purposes set forth.

In testimony whereof, I, the said SAMUEL S. ROBERTS, have hereunto set my hand.
